UNITED STATES PATENT OFFICE

MARIUS C. A. LATOUR, OF PARIS, FRANCE, ASSIGNOR TO GENERAL ELECTRIC COMPANY, A CORPORATION OF NEW YORK.

ALTERNATING-CURRENT MOTOR.

No. 841,544.

Specification of Letters Patent.

Patented Jan. 15, 1907.

Application filed August 25, 1905. Serial No. 275,745.

To all whom it may concern:

Be it known that I, MARIUS C. A. LATOUR, a citizen of France, residing at Paris, France, have invented certain new and useful Improvements in Alternating-Current Motors, of which the following is a specification.

My invention relates to dynamo-electric machines of the commutator type, and is particularly applicable to alternating-current motors.

As is well-known in the art, commutation in alternating-current machines is attended by difficulties which are not present in direct-current machines, since in the former type an armature-coil when short-circuited by a brush in commutation is subjected to an alternating flux which induces short-circuit currents in the coil, which result in sparking and excessive heating. This difficulty is most pronounced at starting when the flux is at a maximum. In order to avoid these short circuits in alternating-current machines of the commutator type, it has been proposed heretofore to wind the armature with a plurality of independent windings and to connect these windings to successive commutator-segments. With such an arrangement and with brushes of a certain width no short-circuit currents are produced. For instance, if three independent windings are employed each segment is separated from the nearest segments connected to the same winding by two other segments, so that if a brush is used of a width not greater than two segments the brush can never bear on two segments at the same time which are connected to the same winding. While this arrangement theoretically improves commutation by avoiding the production of short-circuit currents, it has been found in practice that certain difficulties arise. In every machine the number of slots has a certain maximum value above which it cannot be carried without reducing the size of the teeth to such an extent as to increase the reluctance of the magnetic circuit unduly. The number of slots is usually made as great or nearly as great as is compatible with good design in order to secure the maximum distribution of the winding, and consequently the minimum reactance. When a plurality of independent windings are employed, it is clearly necessary either to sacrifice this distribution or else to distribute

each winding in every slot. The latter is the preferable course and the one that has been employed heretofore. It, however, is subject to the following objection: The coils of the several windings in a given slot necessarily have induced voltages of the same phase, since they are in the same position on the armature-core; but these coils are connected to successive commutator-segments, so that the induced voltages at the commutator-segments do not correspond in phase with the angular positions of the segments. The result as far as commutation is concerned is precisely the same as though the brush were shifted back and forth every time a slot passes the brush. It is evident that the best conditions for commutation are not obtained.

My invention consists in distributing each winding through all the slots and in so connecting the commutator-leads to the several coils that the induced voltage at each lead corresponds in phase to the angular position of the commutator-segment to which it is connected.

More specifically stated, my invention consists in connecting adjacent leads to the several coils in a slot at points on the respective coils differing by a number of turns which bears to the number of turns in a coil a ratio equal to one divided by the number of different windings in that slot—that is, if three windings are used the lead from one segment could be connected to the beginning of a coil of one winding, the next lead would be connected to the coil of the second winding in the same slot at a point one-third the number of turns from the beginning, and the next lead would be connected to the third coil in the slot at a point two-thirds of the turns from the beginning. It will be seen that this arrangement gives a regular progression of the induced voltages at each lead, so that the phase of the induced voltages at the several segments corresponds to the angular position of the segments.

My invention will best be understood by referring to the accompanying drawings, in which—

Figure 1 shows diagrammatically a development on a plane surface of an armature arranged in accordance with my invention, and Figs. 2 and 3 show diagrammatic views of the end of the armature-core with coils

ranged and connected in accordance with my invention.

In Fig. 1 I have shown a diagram of an armature arranged in accordance with my invention reduced to its simplest terms in order to avoid unnecessary complication of the drawing. Thus I have shown only two independent windings, one of these, A, shown in full lines and the other, A', shown in dotted lines. Each winding is shown as having only one coil per slot and only two turns per coil. It will be understood that these specific values have been chosen for the sake of simplicity and that in practice any number of independent coils of any number of coils per slot and any number of turns per coil may be employed. The windings are carried in slots on the core C. The winding A is provided with commutator-leads a, which are connected at one end in the usual manner to points between adjacent coils and at the other end to alternate segments of the commutator c.

a' represents commutator-leads connecting the other winding A' to the remaining segments of the commutator c. It will be seen that these leads a' are not connected to the beginning of the coil in the usual manner, but are connected to the middle of the several coils. With this arrangement it will be seen that a regular progression of phase of induced voltage at the several commutator-segments is obtained. The phase of the voltage induced between any pair of commutator-leads a is the phase of the voltage induced in the coil to the opposite ends of which they are connected, while the phase of the induced voltage between any pair of adjacent leads a' is the phase of the resultant of the voltages in two adjacent coils—that is, it is half-way between the phases of the induced voltages in the two coils.

On the commutator are placed brushes B B, which are of a width equal to or a little less than the width of a commutator-segment. No brush consequently can bridge two segments connected to the same winding, and therefore no short circuits can be produced in commutation. Since the phase of the induced voltage of each commutator-segment corresponds to the angular position of the segment, the difficulty that has heretofore existed in machines provided with independent windings does not exist. If the brush is placed in the best position for commutation with respect to any one winding, it will also be in the best position for commutation with respect to the other winding or windings.

In Fig. 2 I have shown diagrammatically three superposed windings composed of coils of three turns each in each slot of the core C. One winding A is shown in heavy lines, the second winding A' in dotted lines, and the third winding A'' in light lines. a, a', and

a'' represent leads from the respective windings to the commutator c, and these leads are connected to different points on the several coils in the manner heretofore explained. In this case, since there are three coils, the 70 connections to the several coils differ by a number of turns equal to one-third the total number of turns per coil. Since there are three separate windings, the brush B may be of a width equal to two commutator-segments without bridging segments connected to the same winding. 75

The arrangement of Fig. 2 would not be desirable in practice, since the several windings would have unequal reactances because 80 of their different positions in the slots. One method of arranging the windings so as to obtain equal reactances is shown in Fig. 3. In this figure the three windings instead of being superposed are placed side by side in 85 the slots. Aside from this modification the figure is the same as Fig. 2 and requires no further description.

It will be understood that I do not wish to limit myself to the particular arrangement of 90 windings shown in the drawings. For instance, while in Fig. 1 I have shown what is known as a "parallel" or "lap" winding it is obvious that my invention may be used equally well with what is known as a "series" 95 or "wave" winding. Furthermore, as has been pointed out, the number of independent windings, the number of coils per slot, and the number of turns per coil may be varied 100 as desired to meet the requirements of each case.

What I claim as new, and desire to secure by Letters Patent of the United States, is—

1. In a dynamo-electric machine, a slotted armature-core, a commutator carried thereby, a plurality of independent windings distributed in said slots, each slot containing coils belonging to a plurality of said windings, and leads from said coils to successive commutator-segments, said leads being so 105 connected to said coils that the phase of the induced voltage at each lead corresponds to the angular position of the commutator-segment to which it is connected.

2. In a dynamo-electric machine, a slotted 110 armature-core, a commutator carried thereby, a plurality of independent windings distributed in said slots, each slot containing coils belonging to each of said windings, leads from said coils to successive commutator-segments, said leads being so connected to said coils that the induced voltages at adjacent leads differ in phase by an amount equal to the electrical angular displacement 115 of adjacent commutator-segments.

3. In a dynamo-electric machine, a slotted 120 armature-core, a commutator carried thereby, a plurality of independent windings distributed in said slots, each slot containing coils belonging to a plurality of said wind- 125

130

ings, and leads from said coils to successive commutator-segments, adjacent leads being connected to their respective coils at points on the coils differing in position by a number 5 of turns bearing the same ratio to the number of turns in a coil that unity bears to the number of independent windings in the slot.

4. In a dynamo-electric machine, a slotted armature-core, a commutator carried thereby, N independent windings distributed in 10 said slots, each slot containing one or more coils of each winding, and leads from said coils to successive commutator-segments, adjacent leads being connected to their respective coils at points on the coils differing in position by a number of turns bearing to the 15 number of turns in a coil the ratio $\frac{1}{N}$.

5. In a dynamo-electric machine, a slotted 20 armature-core, a commutator carried thereby, a plurality of independent windings distributed in said slots, each slot containing coils belonging to a plurality of said windings, leads from said coils to successive commutator-segments, said leads being so connected 25 to said coils that the induced voltages at ad-

jacent leads differ in phase by an amount equal to the electrical angular displacement of adjacent commutator-segments, and brushes bearing on the commutator of a width insufficient to bridge two segments connected to the 30 same winding.

6. In a dynamo-electric machine, a slotted armature-core, a commutator carried thereby, N independent windings distributed in 35 said slots, each slot containing one or more coils of each winding, leads from said coils to successive commutator-segments, adjacent leads being connected to their respective coils at points on the coils differing in position by a number of turns bearing to the 40 number of turns in a coil the ratio $\frac{1}{N}$, and brushes bearing on the commutator of a width not greater than $(N - 1)$ segments. 45

In witness whereof I have hereunto set my hand this 24th day of August, 1905.

MARIUS C. A. LATOUR.
